and the sea is so rough and turbulent that a landing of seaplanes has been denied due to the violence of the waves, particularly when such turbulent seas are running transversely and perpendicular to the landing and take-off lines. Another difficulty and disadvantage which often occurs is the frequent inclination of the sea which makes the landing and take-off of seaplanes and flying boats difficult to accomplish in turbulent or hazardous water.

FLOATING BREAKWATER FOR SEAPLANES, FLYING BOATS, AND FOR OTHER USES

Edward W. McVitty, New York, N. Y.

Application July 13, 1944, Serial No. 544,686

3 Claims. (Cl. 114—43.5)

This invention relates to an apparatus for providing a landing for seaplanes and the like.

The invention is intended for use in bodies of water which at times are so rough as to make landings of seaplanes, flying boats and the like, hazardous and unsafe. The use of this invention will reduce the roughness of such large bodies of water in restricted areas, sufficient to permit the safe landing of seaplanes, flying boats and the like in such areas, without damage to the planes, and facilitate the mooring thereof in rough seas. Under certain conditions the reduction of the roughness of the sea by the use of this invention will permit the take-off of seaplanes and flying boats without damage to them. The invention has other and extended uses such as creating substantially calm water on an unprotected shore for boats, during loading and unloading, either from a dock or beach.

In the drawing, Fig. 1 represents a plan view of the floating breakwater of this invention, illustrated as anchored in a large body of water, showing a seaplane in the act of landing upon the lee side of the breakwater; Fig. 2 is an end sectional view of the device of Fig. 1; Fig. 3 is a detailed enlargement of some of the units making up the breakwater; and Fig. 4 is an end view on the line 4—4 of Fig. 3.

The floating breakwater of this invention is composed of a multiplicity of floating members 1, which are so constructed as to be water-tight and float with a portion thereof above water. The floats 1 are arranged in spaced relation in a series of parallel rows. The two outer rows 2 and 3 arranged in lengthwise direction and the two crosswise rows 4 and 5, are secured, respectively, to the flexible lengthwise supports 6—7 and the crosswise supports 8—9. At the point of junction of a lengthwise support and a crosswise support, the ends thereof are connected by a suitable ring member 10. Each unit 1 of the outer rows of supports is connected at two places to its corresponding support by flexible connection 11, excepting that the corner floats are connected by three flexible connections to the supports. One of the flexible connections for the corner unit extends to the lengthwise support and one to a crosswise support and the third to the point of junction 10 of a crosswise support and a lengthwise support. Additional floating members 1 are arranged inside of the outer rows of such floating members and are connected to the outer rows of floating members and to each other by flexible connections 12. Each of the floating members is provided with a suitable connecting

eye 13, from which the flexible connections extend from the outer supports 6—9 or to an eye of an opposite float.

The four corners of the breakwater are each provided with a chain or rope and anchor, which, when dropped to the sea or water bottom, will anchor the floating breakwater in extended condition, retaining the individual floats in non-contacting relation.

The flexible connections 6, 7, 8 and 9 may be made of metal cable, chain or rope, or other flexible material which has the capacity of readily bending to permit the floats to have a considerable degree of independent movement.

The entire breakwater is in the form of a large web and when in anchored position is retained in a stretched condition by the four anchors 18, the connection between the floating members being taut. When the breakwater is in anchored position, the pull of the anchor tends to pull the peripheral supports 6—9 under water, but the outer rows of floats 1 will remain above water in floating position as illustrated in Fig. 2. Assuming that the breakwater of this invention has been anchored and encounters rough water, the waves will strike the outermost row of floats 1 and the force thereof will be initially damped. As the water proceeds toward the successive rows of floats and impacts such floats, its force will be successively reduced or damped, providing a body or area of water on the lee side of the floating breakwater for the landing or mooring of seaplanes and the like, for the loading and unloading of boats upon beaches or at docks and for other use requiring substantially calm water in an area in which the sea would normally be rough. By attaching the floating members to one another, a large degree of independence of motion is permitted between the successive rows of floating units. The flexible connection between the floats is also a factor in reducing the degree of impact transmitted from row of floats to row of floats. This is desirable inasmuch as the entire breakwater does not move as a unit but rather as a multiplicity of units, each resisting quite independently whatever wave forces may reach it.

I claim:

1. A breakwater for reducing the force of waves comprising a series of floats, each float being connected to an adjoining float by a flexible connection, a series of flexible connecting members forming the outside of said breakwater, the floats at the outer portion of the breakwater being individually connected to said flexible connecting

members, ends of said connecting members converging together and being secured together, anchors attached at a series of spaced points to said connecting members for holding the floats apart.

2. A breakwater according to claim 1, in which the float units are arranged in rows and the units of adjoining rows are arranged in staggered relation.

3. A breakwater for reducing the force of waves to provide a lee side, comprising a series of flex-

ible connecting members arranged at the outside of said breakwater and extending continuously therearound, anchors arranged at a plurality of points on said breakwater, float units arranged within said connecting members, the individual float units being spaced apart, the outer rows of float units being connected with said connecting members, each float unit inside of said outer units being connected to a plurality of float units.

EDWARD W. McVITTY.
